SIDE BEARING

Paul V. Larsen, Chicago, Ill., assignor to Pettibone Mulliken Company, Chicago, Ill., a corporation of Delaware

Application May 27, 1935, Serial No. 23,575

1 Claim. (Cl. 308—226)

This invention relates to a novel and improved side bearing, and consists of the matters herein-after described and more particularly pointed out in the appended claim.

5 The object of the invention is to produce a novel and improved form of side bearing, including a roller casing and filler plate constructed and arranged for use with shims for vertical adjustment of the fill plate, with novel means for retaining the filler plate and shims in position when mounted on a bolster, but permitting ready access to said shims for insertion, removal or replacement, to vary the level of the filler plate.

In the drawings:—

15 Figure 1 is a view representing a top plan of the improved side bearing;

Figure 2 is a side elevation of the side bearing with parts shown in vertical section as indicated by the line 2—2 of Figure 1;

20 Figure 3 is an end view of the side bearing with parts shown in vertical section;

25 Figure 4 is a partial perspective view of an end of the casing with the plate and shim retaining member removed and in vertical position above the place which it is to occupy when in position on the end of the casing; and

Figure 5 is a like view but showing said plate and shim retaining member in proper position and secured to the end of the casing.

30 In the drawings:—10 indicates the casing and 11 indicates the filler plate, which also constitutes the wear plate. 12 indicates the anti-friction roller and 13, 13 indicate shims located below the filler plate,—it being understood, of course, that the casing and shims rest directly on the bolster.

35 The casing 10 is a hollow shell, open top and bottom, and provided with laterally extending apertured lugs 14 at the base for attachment to the bolster by means of bolts or lag screws,—in a familiar manner. The casing has side walls 15, 15 and end walls 16, 17. In the side walls are formed horizontal ways or channels 18, in which travel short studs 19 on the ends of the roller and 40 co-axial therewith. Said ways or channels extend in each direction from the middle of the casing a distance sufficient to provide accommodation for the designed travel of the roller.

45 The combined wear plate and filler block 11 is loose in the casing and is of a familiar form, in the main having a wear surface 20 inclined in opposite directions from a transverse median line for the purpose of centering the roller and having transverse bottom ribs 21, one at the middle 50 and one at each end, which present bearings or

rests for the filler block for supporting engagement against the bolster or the shims interposed between said bolster and the said ribs. Horizontal ribs 15a, 15a on the side walls and 16a, 17a on the end walls, limit the vertical movement of the 5 filler block in the casing, said filler block loosely fitting within the sides and ends of the casing below said ribs, so as to be movable therein for vertical adjustment by insertion or removal of one or more shims between the bottom of said wear 10 plate and the bolster.

On the end wall 17 and projecting therefrom, is a fitting 22, preferably made integral with said casing. 23 indicates a downwardly tapered stud provided throughout the greater part of its length 15 with flat lateral flanges 24, 24 and a top flange 25 extending at right angles to said lateral flanges.

The fitting 22 is provided with a way 22a between the proximate surface of the end wall 17 of the casing, as shown in Figure 4. This way 20 is similar in transverse and vertical section to that of the stud, with its lateral flanges 24 so that the stud 23 may be dropped into the way, being arrested in its downward movement by the horizontal top flange 25, which acts as a stop to engage the horizontal top end 22b of the fitting 22. When in this position, the bottom end 23a of the stud projects below the bottom plane of the casing 10, as clearly shown in Figures 2, 3 and 5, to engage with one of the usual holes or openings 30 26 generally provided in the top plate of the car truck bolster 26a for attachment to side bearings of different designs. For easy access to said hole, said bottom end part 23a of the stud is slightly more tapered than the main body of the 35 stud.

A transverse groove 23b is formed in the stud intermediate its ends. The fitting 22 is formed to provide a cylindrical hole or opening 27 extending horizontally and intersecting the part 40 of the way which receives the stud, so that a bolt 28 inserted through said hole will engage the groove 23b in the stud and act to lock said stud in the fitting 22.

The end wall 17 of the casing terminates considerably above the plane of the bottom of the casing to leave a transverse opening 17b extending the full width of the casing. Into this opening extend the shims 13, as shown in Figure 2, said shims being longer than the wear plate, as 45 shown in Figures 2 and 3. It will be observed that this opening is blocked when the stud 23 is in final position in the fitting 22. When the bearing is first assembled, ready for attachment to the bolster, one or more shims 13 may be in- 50 55

serted with the wear plate 11 through the opening in the bottom of the casing. After the casing is bolted to the bolster, further adjustment of the vertical position of the wear plate 11 may 5 be made by removing the bolt 28 from the fitting 22 and lifting the stud 23 so as to permit access to the opening 17a in the end wall. After, an additional shim or shims may then be inserted through said opening 17a. The stud 23 is then 10 replaced in its way in the fitting 22 and is again locked in position by the bolt 28.

After the bearing has been in use and begins to show wear, it is a very simple operation to 15 remove the stud 23 in the manner described and insert an additional shim or shims, as required.

The construction described is very simple and efficient, is readily capable of economical manufacture and easy adjustment to take up or provide for wear.

20 I claim as my invention:

A casing for side bearings, consisting of an elongated shell having side walls and end walls and being open at the top and bottom, said side

walls and end walls being provided with horizontal ribs spaced above the bottom of the casing, a 5 filler block insertable into said shell through its bottom, one or more shims insertable into said shell from the bottom following said filler block, one end wall of said casing terminating short of the bottom plane of said casing to leave a transverse opening extending the width of said casing, a fitting on the outside of said end wall made rigid therewith, said fitting being provided 10 with a vertically extending, downwardly tapering way opening into lateral, vertical grooves adjacent said end wall, a tapered stud having lateral flanges insertable downwardly into said way and grooves and having a top flange adapted to 15 limit its movement, said stud projecting below the bottom of said casing when seated in its way and being provided with a transverse groove intermediate its ends, and said fitting being provided with a transverse hole adapted to intersect said groove in said stud, and a bolt taking through said hole for locking said stud in position.

PAUL V. LARSEN.
